Patented June 24, 1975

235,490

COMBINED BELT AND DETACHABLE COMPARTMENTS

James D. Lewis, 3716 Indiana St.,
San Diego, Calif. 92103

Filed Dec. 26, 1973, Ser. No. 428,119

Term of patent 14 years

Int. Cl. D2—07

U.S. Cl. D2—381

FIG. 1

FIG. 2

FIG. 3

FIG. 4

FIG. 1 is a front perspective view of a combined belt and detachable compartments showing my new design;

FIG. 2 is a rear perspective view thereof;

FIG. 3 is a side perspective view; and

FIG. 4 is a perspective view of the other side.

I claim:

The ornamental design for a combined belt and detachable compartments, as shown.
